UNITED STATES PATENT OFFICE.

MARION E. STARR, OF MASON CITY, IOWA.

COMBINED HOT-WATER BOTTLE AND SYRINGE.

1,157,439.

Specification of Letters Patent. Patented Oct. 19, 1915.

Application filed April 28, 1915. Serial No. 24,456.

To all whom it may concern:

Be it known that I, MARION E. STARR, a citizen of the United States, residing at Mason City, in the county of Cerro Gordo, 5 State of Iowa, have invented certain new and useful Improvements in Combined Hot-Water Bottles and Syringes; and I do hereby declare the following to be a full, clear, and exact description of the invention, such 10 as will enable others skilled in the art to which it appertains to make and use the same.

This invention relates to improvements in combined hot water bottles and fountain 15 syringes.

The principal object of the invention is to provide a novel device of this character in which a disinfectant and a sterile water can be used in succession without the delay of 20 refilling the fountain.

Another object is to provide a device of this character in which either a disinfectant or pure sterile water can be used, each independently of the other.

25 Other objects and advantages will be apparent from the following description when taken in connection with the accompanying drawing.

In the drawing: Figure 1 is a plan view of 30 a combined hot water bottle and fountain syringe made in accordance with my invention, Fig. 2 is an edge view thereof, and Fig. 3 is a longitudinal sectional view on the line 3—3 of Fig. 1.

35 Referring particularly to the accompanying drawing, 10 represents a canvas, rubber, or combined canvas and rubber sheet on one face of which are secured two elongated rubber bags 11 and 12.

40 Connected together at their inner ends by a pipe 13 in which is mounted a stop cock 14. One end of the sheet 10 is formed with a loop 15 by means of which the same can be hung up at a convenient point. In the 45 outer end of each of the bags 11 and 12 is a funnel-shaped mouth 16 through which the bags are filled, each mouth being provided with a suitably threaded plug stopper 17. A pipe 18 is provided at one end with a thread-

ed nipple 19 for engagement in either one of 50 the filling openings 16, while at the opposite end there is provided a suitable nozzle 20. A suitable check 21 is provided on the pipe for controlling the flow of liquid from the bags.

55 In the use of the device, with the stop cock 14 closed, the bag 12 is filled with a suitable disinfectant solution, the pipe 18 engaged in the opening thereof, and the bag 11 then filled with sterile water. The device 60 is next suspended from a nail or the like by means of the loop 15 and the disinfectant permitted to flow from the bag 12 and through the pipe 18. After the bag 12 is emptied the stop cock 14 can be opened and the sterile water permitted to flow into the bag 12 and then out through the pipe 18. Thus the disinfectant can be used and then 65 the sterile water in rapid succession without the necessity of refilling either of the bags. Attention is also called to the fact that after the disinfectant has been drained from the bag 12 and the sterile water from the bag 11 allowed to run thereinto, the bag 11 can be again filled so that a double quantity of 70 sterile water can be used. The bag 11 can be filled at the same time that the bag 12 is being emptied whereby considerable time is 75 saved.

By placing plug stoppers in the ends of 80 the two bags, the same can be used as a hot water bottle, as will be readily understood.

What is claimed is:

A combined hot water bottle and syringe fountain comprising a base provided with 85 suitable suspending means, a pair of fluid containers supported on the base and provided with combined filling and discharge openings at their outer ends arranged for connection with a fluid conducting pipe, and 90 a valved connection between the inner ends of the containers.

In testimony whereof, I affix my signature, in the presence of two witnesses.

MARION E. STARR.

Witnesses:

JOHN SMITH,
ANNA ELLISON.
